(57) **CLAIM**

I claim the ornamental design for a candle holder, as shown and described.

DESCRIPTION

FIG. 1 is a perspective view of a first embodiment of a candle holder according to my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a perspective view of a second embodiment of a candle holder according to my new design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The part of the photographs shown in a coarse dot pattern, along with the broken-line perimeter illustrates portions of the candle holder that forms no part of the claimed design.
